(57) **CLAIM**

The ornamental design for a lock, as shown and described.

DESCRIPTION

FIG. 1 is a front perspective view of a lock showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded perspective view thereof, shown in disassembled condition.

FIG. 9 is another exploded perspective view thereof, shown in alternate position of its disassembled condition;

FIG. 10 is an exploded perspective view thereof; and,

FIG. 11 is another exploded view thereof, in alternate position.

The broken line environment is for illustrative purpose only and forms no part of the claimed design.
